CLIP FOR A WRITING INSTRUMENT

Michael P. Arnone, North Bergen, N.J., assignor to
Kreisler Manufacturing Corporation, North Bergen,
N.J.

Filed Apr. 19, 1971, Ser. No. 135,516

Term of patent 14 years

Int. Cl. D19—99

U.S. Cl. D74—17

FIG. 1 is a front elevation of a clip for a writing instrument showing my new design.

FIG. 2 is a side elevation of the clip shown in FIG. 1, the other side being a mirror image thereof;

FIG. 3 is a top plan view thereof;

FIG. 4 is a bottom plan view thereof; and

FIG. 5 is a rear elevation thereof.

I claim:

The ornamental design for a clip for a writing instrument, substantially as shown and described.
